US0D1008894S

(12) **United States Design Patent** (10) **Patent No.:** **US D1,008,894 S**
Yao (45) **Date of Patent:** **** Dec. 26, 2023**

(54) **BUMPER**

- (71) Applicant: **HUMAN HORIZONS (JIANGSU) TECHNOLOGY CO., LTD.**, Yancheng (CN)
- (72) Inventor: **Yucheng Yao**, Yancheng (CN)
- (73) Assignee: **HUMAN HORIZONS (JIANGSU) TECHNOLOGY CO., LTD.**, Yancheng (CN)

(**) Term: **15 Years**(21) Appl. No.: **29/834,831**(22) Filed: **Apr. 14, 2022****Related U.S. Application Data**

- (62) Division of application No. 29/771,372, filed on Feb. 22, 2021, now Pat. No. Des. 971,093.
- (51) **LOC (14) Cl.** **12-16**
- (52) **U.S. Cl.** USPC **D12/169**
- (58) **Field of Classification Search**
 USPC D12/86, 90, 91, 92, 98, 163, 164, 169, D12/190, 196
 CPC B60R 19/02; B60R 19/04; B62D 25/08
 See application file for complete search history.

(57) **CLAIM**

The ornamental design for a bumper, as shown and described.

DESCRIPTION

FIG. 1 is a front view of the bumper showing my new design;

FIG. 2 is a rear view thereof;

FIG. 3 is a left side view thereof;

FIG. 4 is a right side view thereof;

FIG. 5 is top view thereof;

FIG. 6 is a bottom view thereof; and,

FIG. 7 is a front, left perspective view thereof.

The broken lines shown in the figures depict portions of the bumper that show no part of the claimed design.

1 Claim, 7 Drawing Sheets
